EJECTOR TYPE REFRIGERATING SYSTEM

Original Filed June 6, 1934

UNITED STATES PATENT OFFICE

2,132,322

EJECTOR TYPE REFRIGERATING SYSTEM

Joseph E. Robb, Kansas City, Kans., assignor to
Minneapolis-Honeywell Regulator Company,
Minneapolis, Minn., a corporation of Delaware

Original application June 6, 1934, Serial No.
729,252. Divided and this application November
20, 1935, Serial No. 50,688

16 Claims. (Cl. 62—152)

This invention relates to cooling or refrigerating systems, and more particularly to that type of system utilizing a steam jet ejector. This application is a division of copending application 5 Serial No. 729,252, filed on June 6, 1934.

An object of this invention is to provide a cooling system of the class described with safety devices and control devices whereby an efficient and safe operation of such a cooling system may be 10 obtained.

It is an object of this invention to provide a control system for a cooling system having an evaporator, an ejector, a condenser and a boiler wherein the boiler is placed in operation in response to a condition to be controlled and wherein the ejector is placed in operation in response to boiler pressures.

It is another object of this invention to provide a control system for a cooling system of the type 20 described above wherein the boiler is protected by means of a safety pilot control, a high limit control, a low-water cut-off control and a control device responsive to the vacuum in the condenser.

25 It is another object of this invention to provide safety controls for a cooling system of the type outlined above wherein control devices responsive to evaporator temperatures are utilized to prevent operation of the ejector in case the evaporator 30 temperature becomes too low or too high.

Still another object of this invention is to provide a refrigerating system of the type utilizing a condenser, an ejector, an evaporator and a boiler with means for controlling the flow of cooling 35 fluid to a point of use, means for controlling the flow of condensing water to the condenser, means for controlling the operation of the ejector and means for controlling the operation of the boiler wherein the boiler operating means is controlled 40 in response to a condition to be controlled and in response to the condition of the boiler and the vacuum in the condenser, wherein the ejector is controlled in response to boiler pressures and evaporator temperatures and wherein the means 45 for controlling the flow of cooling fluid and condensing water is controlled in response to boiler pressure and evaporator temperatures.

Other objects and advantages will become apparent to those skilled in the art upon reference 50 to the accompanying specification, claims and drawing, in which drawing is diagrammatically illustrated the cooling or refrigerating system of my invention.

Referring now to the drawing, the evaporator is designated at 10 and is connected by a steam

jet ejector 11 to a condenser 12 in the manner known in the art. Steam is supplied to the ejector 11 by means of a pipe 13 under the control of a valve 14. The pipe 13 is connected into a steam header 15 leading from a boiler shown at 16. The valve 14 controlling the supply of steam from the boiler 16 to the ejector 11 is controlled by means of a motor 17, of a type well known in the art, which moves the valve 14 to either an extreme closed or an extreme open position. Condensed steam is drawn from the condenser 12 through a pipe 18 and is fed back to the boiler 16 by means of a circulating and vacuum pump 19.

The condenser coil diagrammatically illustrated at 20 in the condenser 12 is connected by pipes 21 and 22 to a cooling tower generally designated at 23. The warm condensing water is drawn from the condenser 12 through the pipe 22 by the circulating pump 24 and is sprayed in the cooling tower 23 by means of a spray 25. A fan 26 for forcing relatively cool air in the cooling tower aids in the cooling of the condensing water. The cooled condensing water is returned from the tower 23 to the condenser coil 20 by the pipe 21.

The evaporator 10 is connected by pipes 29 and 30 to a cooling coil 31 which may be located in a conditioning unit generally designated at 32. The cooling fluid is circulated through the evaporator 10, the pipes 29 and 30 and the cooling coil 31 by means of a circulating pump 33.

The operation of this type of cooling system is well known in the art and a detailed description thereof is not considered necessary, it being sufficient to state that upon opening of the valve 14 steam is admitted to the ejector 11 to create a vacuum in the evaporator 10 and by reason of this vacuum the cooling fluid leading from the cooling coil 31 and sprayed into the evaporator 10 is cooled and returned by the pipe 30 to the cooling coil 31, whereby the temperature within the conditioning unit 32 is lowered. The steam used in this cooling of the cooling fluid is condensed within the condenser 12 and returned to the boiler 16.

For purposes of illustration, a gas burner 35 has been shown for firing the boiler 16. Gas is supplied to the gas burner 35 through a supply pipe 36 under the control of a gas valve 37 operated by a motor means 38. The motor means 38 is well known in the art and it is sufficient to state that upon energization of the motor means 38 the valve 37 is opened, and upon deenergization thereof the valve 37 is closed. A pipe 39 leading from the gas supply pipe 36 ahead of the valve 37 connects to a pilot light 40, and responding to

30

35

40

45

50

55

the pilot light 40 is a bimetallic element 41 which is adapted to engage a contact 42. When the pilot light 40 is lit, the bimetallic element 41 engages the contact 42, and if the pilot light 40 should become extinguished the bimetallic element 41 disengages the contact 42.

For purposes of safe-guarding the operation of the boiler 16, this invention contemplates the use of a low-water cut-off mechanism generally 10 designated at 43 and operating a switch 44, the arrangement being such that when the level of the boiler water is normal the switch 44 is in a circuit-making position as shown in the drawing. This invention also contemplates the use of a 15 high limit safety control mechanism generally designated at 45 and may comprise a bellows 46 connected by a pipe 47 to the steam header 15. The bellows 46 is adapted to operate a pivoted lever 48 which carries a mercury switch 49. The 20 mercury switch 49 is provided with a plurality of contacts, the left-hand ones of which may be designated low pressure contacts, and the right-hand ones may be designated high pressure contacts. The bellows 46 is actuated by the steam 25 pressure within the header 15 and the arrangement is such that when the steam pressure is normal the left-hand or low pressure contacts are engaged by the mercury, and if the pressure within the boiler 16 should become excessive the mercury switch 49 is tilted so that the mercury engages the high pressure contacts. The high limit switch 45 may be adjusted so that it will be tilted to the position opposite that shown in the drawing when the boiler pressure exceeds, say, 16 30 pounds.

A vacuum switch is generally designated at 51 and may comprise a bellows 52 connected by a pipe 53 to the interior of the condenser 12. The bellows 52 operates a pivoted lever 54 which carries a mercury switch 55. The mercury switch 40 55 is therefore operated in response to vacuum existing within the condenser 12 and the mechanism 51 is preferably adjusted so that the mercury switch 55 is moved to a circuit-making position upon the occurrence of 26 inches of 45 mercury vacuum in the condenser 12.

A pressure switch designated generally at 57 may comprise a bellows 58 which is connected by a pipe 59 to the pipe 13 ahead of the valve 14. The bellows 58 operates a pivoted lever 60 50 which carries a mercury switch 61. The mercury switch 61 contains left-hand low pressure contacts and right-hand high pressure contacts, the arrangement being such that when the pressure within the pipe 13 increases to 13 pounds 55 the mercury switch is tilted to the position opposite that shown in the drawing to make contact between the high pressure contacts, and when the pressure within the pipe 13 drops to 60 say 10 pounds the mercury switch 61 is tilted to the position shown in the drawing to make contact between the low pressure contacts.

This invention also contemplates the use of 65 temperature responsive switching mechanisms generally designated at 63 and 70. The temperature responsive switching mechanism 63 may comprise a bellows 64 connected by a capillary tube 65 to a bulb 66 which is located within the evaporator 10. The bellows 64 operates a pivoted lever 67 which carries a mercury switch 68. The temperature responsive switching mechanism 70 70 may comprise a bellows 71 connected by a capillary tube 72 to a bulb 73 also located within the evaporator 10. The bellows 71 operates a pivoted lever 74 which carries a mercury switch 75.

The mercury switch 68 of the temperature responsive device 63 contains a plurality of contacts, the arrangement being such that when the temperature within the evaporator decreases to say 40°, the mercury switch is tilted from the 5 position shown in the drawing to a position wherein the left-hand contacts are made. The mercury switch 68 is normally in the position shown in the drawing. The mercury switch 75 10 of the temperature responsive device 70 also contains a plurality of contacts and the arrangement is such that when the temperature within the evaporator 10 increases to a predetermined high value, say 60°, the mercury switch 75 is tilted to make contact between the left-hand contacts 15 thereof. The mercury switch 75 is normally maintained in the position shown in the drawing.

A time switch is generally designated at 77 and 20 may comprise a cam 78 which operates a pivoted lever 79, which in turn carries a mercury switch 80. The cam 78 may be operated by means of a rotor, not shown, and a field winding 81 in the manner well known in the art. The arrangement is such that during day-time, the mercury 25 switch is maintained in a circuit-making position, and during night periods when it is desired to have a shut-down of the cooling system the mercury switch may be moved to a circuit-breaking position.

A condition responsive device is generally designated at 83 and for purposes of illustration, this condition responsive device is shown to comprise a bimetallic element 84 responding to changes 30 in the temperature to be controlled. The bimetallic element 84 operates a carrier 85 which carries a mercury switch 86, the arrangement being such that upon an increase in temperature as affecting the bimetallic element 84, the carrier 85 is moved in the direction indicated by the 40 character H to move the switch 86 to a circuit-making position.

A relay is generally designated at 88 and comprises a relay coil 89 for operating switch arms 90 and 91. Upon energization of the relay coil 45 89 the switch arms 90 and 91 are moved into engagement with contacts 92 and 94, and upon deenergization of the relay coil 89, the switch arms 90 and 91 are moved out of engagement with the contacts 92 and 94 and the switch arm 50 90 is moved into engagement with the contact 93.

A relay generally designated at 95 comprises an energizing coil 96 and a bucking coil 97 for operating switch arms 98 and 99, the arrangement being such that when the energizing coil 55 96 is energized, switch arms 98 and 99 are moved into engagement with contacts 100 and 101, and when the energizing coil 96 is deenergized or when the energizing coil 96 and the bucking coil 97 are both energized the switch arms 98 and 60 99 are moved out of engagement with the contacts 100 and 101.

Another relay generally designated at 102 comprises a relay coil 103 which moves a switch arm 104 into engagement with a contact 105 upon 65 energization thereof. This invention also contemplates the use of three more relays generally designated at 106, 110 and 114, respectively, the relay 106 comprising a relay coil 107 operating a switch arm 108 with respect to a contact 109, 70 the relay 110 comprising a relay coil 111 for operating a switch arm 112 with respect to a contact 113 and the relay 114 comprising a relay coil 115 for operating a switch arm 116 with respect to a contact 117.

Line wires 120 and 121 leading from some source of power, not shown, are connected to a primary 122 of a step-down transformer 123 having a secondary 124. One end of the secondary 124 is connected by a wire 125 to one of the electrodes of the mercury switch 86, and the other electrode thereof is connected by a wire 126 to one end of the relay coil 89. The other end of the relay coil 89 is connected by a wire 127 to the other end of the secondary 124. Upon an increase in temperature as affecting the bimetallic element 84 the mercury switch 86 is moved to a circuit-making position to complete a circuit from the secondary 124, through wire 125, mercury switch 86, wire 126, relay coil 89 and wire 127 back to the secondary 124. Energization of the relay coil 89 causes movement of the switch arms 90 and 91 into engagement with the contacts 92 and 94, respectively. Movement of the switch arm 91 into engagement with the contact 94 completes a circuit from a line wire 129, through wire 131, mercury switch 80, wire 132, contact 94, switch arm 91, wire 133, wire 134, relay coil 103 of relay 102 and wires 135 and 136 back to the other line wire 130, providing the mercury switch 80 is maintained in a circuit-making position as for day operation. Completion of this circuit causes energization of the relay coil 103 to move the switch arm 104 into engagement with the contact 105 to complete a circuit from a line wire 160, through switch arm 104, contact 105, wire 162, electrically operated vacuum pump 19 and line wire 161. Completion of this circuit causes operation of the vacuum pump 19 to draw condensate from the condenser 12 and to produce a vacuum therein.

When the vacuum within the condenser 12 so produced reaches, say 26 inches of mercury, the switch 55 of the vacuum responsive device 51 is moved to a circuit-making position to complete a circuit from the line wire 129, through wire 131, mercury switch 80, wire 132, contact 94, switch arm 91, wires 133 and 137, mercury switch 55, wire 138, mercury switch 44 of the low-water cut-off mechanism 43, wire 139, primary 140 of a step-down transformer 141 having a secondary 142, and wires 143 and 136 back to the line wire 130. Completion of this circuit causes energization of the step-down transformer 141. The transformer 141 will remain energized so long as the mercury switches 86, 88, 55 and 44 are maintained in a circuit-making position. Therefore, if the temperature or condition to be controlled becomes satisfied, if night operation is desired, if the vacuum within the condenser 12 falls below 26 inches of mercury, or if the liquid level within the boiler 16 should decrease to an abnormally low value the transformer 141 will become deenergized.

60 The motor 38 for operating the gas valve 37 is connected in parallel with the primary 140 of the step-down transformer 141 by wire 144, contact 101, switch arm 99 and wires 145 and 146. Therefore, when the switch arm 99 is moved into engagement with the contact 101 the motor 38 of the gas valve 37 will be energized to open the gas valve 37 as long as the transformer 141 is supplied with power, the safety features protecting the operation of the transformer 141 also

70 protecting the operation of the gas valve 37. Movement of the switch arm 90 into engagement with the contact 92 in the manner pointed out above completes a circuit from one end of the secondary 142, through wire 148, contact 42, bimetallic element 41, wire 149, wire 150, contact

92, switch arm 90, wire 152, low pressure contacts of the mercury switch 49, wire 153, energizing coil 96 of the relay 95, wire 154 and wire 155 back to the secondary 142. Completion of this circuit causes movement of the switch arms 98 and 99 into engagement with the contacts 100 and 101. Movement of the switch arm 99 into engagement with the contact 101 causes opening of the gas valve 37 and consequent firing of the boiler 16. Movement of the switch arm 98 into engagement with the contact 100 completes a maintaining circuit through the energizing coil 96 from the secondary 142, through wire 148, contact 42, bimetallic element 41, wires 149 and 151, switch arm 98, contact 100, energizing coil 96 and wires 154 and 155 back to the secondary 142. In this manner, the energizing coil 96 is maintained energized to maintain the valve 37 open as long as the step-down transformer 141 is energized in the manner pointed out above. If the boiler pressure should increase to an abnormally high value, to say 16 pounds, so as to move the mercury switch 48 to a position opposite to that shown in the drawing, a circuit is completed from the secondary 142, through wire 148, contact 42, bimetallic element 41, wires 149 and 151, switch arm 98, contact 100, wire 153, high pressure contacts of mercury switch 49, wires 157 and 158, bucking coil 97 and wire 155 back to the secondary 142. Completion of this circuit during the existence of abnormally high boiler temperature causes energization of the bucking coil 97 which counter-acts the action of the energizing coil 96 to allow the arms 98 and 99 to move out of engagement with the contacts 100 and 101, respectively. This breaks the circuit to the motor 38 of the gas valve 37 to stop firing of the boiler 16 until such time as the boiler pressure should decrease to a normal value. When the boiler pressure decreases to this normal value the mercury switch 49 is tilted to the position shown in the drawing to break the circuit through the bucking coil 97 to allow energizing coil 96 to move the switch arms 98 and 99 into engagement with the contacts 100 and 101, thereby opening the gas valve 37 to continue the operation of the boiler 16.

If the bimetallic element 84 becomes satisfied so as to move the mercury switch 86 to the circuit-breaking position as shown in the drawing, the switch arm 90 is moved into engagement with the contact 93 as the result of deenergization of the relay coil 89. Movement of the switch arm 90 into engagement with the contact 93 completes a circuit from the secondary 142, through wire 148, contact 42, bimetallic element 41, wires 149 and 151, switch arm 98, contact 100, wire 153, low pressure contacts of the mercury switch 49, wire 152, switch arm 90, contact 93, wires 156 and 158, bucking coil 97 and wire 155 back to the secondary 142. Completion of this circuit causes energization of the bucking coil 97 which counter-acts the action of the energizing coil 96 to allow the switch arms 98 and 99 to move out of engagement with the contacts 100 and 101, respectively. This causes deenergization of the motor 38 with consequent closing of the gas valve 37 thereby preventing the further operation of the boiler 16.

In the manner pointed out above, the boiler 16 is under the direct control of the condition responsive device 83 and the vacuum existing within the condenser 12 so that when the temperature affecting the bimetallic element 84 is above the desired value, and when the vacuum

within the condenser 12 is at the desired value, the boiler 16 is placed in operation. Safety mechanisms are provided whereby operation of the boiler 16 is prevented in case the boiler pressure becomes abnormally high, or the pilot light should be extinguished, or the boiler water level should become abnormally low.

A primary 165 of a step-down transformer 166 having a secondary 167 is connected across the line wires 129 and 130. The secondary 167 is connected by wires 168 and 169 to the valve motor 17 for supplying power thereto. The motor 17 is connected by a wire 170 to the low temperature electrode of the mercury switch 75 operated by the temperature responsive device 70. The common electrode thereof is connected by a wire 171 to the high temperature electrode of the mercury switch 68 of the temperature responsive device 63. The common electrode thereof is connected by a wire 172 to the high pressure contact of the mercury switch 61 of the pressure responsive device 57. The common electrode of mercury switch 61 is connected by a wire 173 to the motor 17. The motor 17 is also connected by wires 174, 175, 176, 177 and 178 to the left-electrodes of the mercury switches 61, 68 and 75 respectively.

When the boiler has been placed in operation in the manner pointed out above, and when the boiler pressure has increased to a predetermined value, say 13 pounds, the mercury switch 61 is moved to a position opposite to that shown in the drawing, and since the mercury switches 68 and 75 are in their normal positions as shown in the drawing a circuit is completed from the secondary 167, through the wires 169, 173, high pressure electrodes of the mercury switch 61, wire 172, mercury switch 68, wire 171, mercury switch 75, wire 170, motor 17 and wire 168 back to the secondary 167. Completion of this circuit causes operation of the motor 17 to move the valve 14 to an open position to supply steam at 13 pounds pressure to the ejector 11 to cause operation of the steam jet refrigerating mechanism. If the evaporator temperature should decrease to such a value, say 40° F., wherein danger of freezing of the steam jet refrigerating mechanism would occur, the mercury switch 68 is tilted to the position opposite to that shown in the drawing to break the above-referred to circuit and to complete a circuit from the secondary 167, through wires 169 and 173, mercury switch 61, wire 172, mercury switch 68, wires 177, 176 and 174, motor 17 and wire 168 back to the secondary 167. Completion of this circuit causes closing of the valve 14 whereby the further supply of steam to the ejector 11 is prevented until such time as the evaporator temperature should increase above the predetermined low value of say 40°. In this manner, freezing of the refrigerating system is prevented.

If for some reason or other the evaporator is not cooled by the operation of the ejector and the evaporator temperature should rise to a value above say 60°, the mercury switch 75 is tilted to a position opposite to that shown in the drawing to break the above opening circuit for the valve 14 and to complete a circuit from the secondary 167, through wires 169 and 173, mercury switch 61, wire 172, mercury switch 68, wire 171, mercury switch 75, wires 178, 176 and 174, motor 17 and wire 168 back to the secondary 167. Completion of this circuit also causes closing of the valve 14. Therefore, if the steam jet refrigerating apparatus fails to function properly for some reason or other so as to allow the temperature of the evap-

orator to rise above a predetermined high value of 60° the valve 14 is closed to prevent the further operation of the steam jet refrigerating apparatus.

When the boiler 16 is deenergized in the manner pointed out above by reason of the condition responsive device 83 being satisfied, the boiler pressure decreases, and when the boiler pressure decreases to a predetermined value of say 10 pounds, the mercury switch 61 of the pressure responsive device 57 is tilted to the position shown in the drawing to break the above-referred to circuit for opening the valve 14 and to complete a circuit from the secondary 167 through wires 169 and 173, mercury switch 61, wires 175 and 174, motor 17 and wire 168 back to the secondary 167. Completion of this last mentioned circuit causes closing of the valve 14.

From the above it is seen that I have provided a means whereby the steam jet refrigerating mechanism is placed in operation when the boiler pressure rises to a predetermined value, and is placed out of operation when the boiler pressure decreases to a predetermined lower value, or when the evaporator temperature; i. e. the temperature of the chilled water, decreases below a predetermined value where freezing is liable to occur, or increases above a predetermined higher value which may be caused by faulty operation of the refrigerating mechanism. In this manner, safe operation of a steam jet refrigerating mechanism is assured.

The motor 17 operates a lever 164 which carries a mercury switch 179, the arrangement being such that when the motor 17 is operated to move the valve 14 to an open position the mercury switch 179 is moved to a circuit-making position, and when the valve 14 is moved to a closed position by the motor 17 the mercury switch 179 is moved to a circuit-breaking position. Movement of the valve 14 to an open position in the manner pointed out above completes a circuit from the line wire 129 through wire 180, mercury switch 179, wire 181 and through three branch circuits, the first being through relay coil 107 of the relay 106 and wire 182 back to the other line wire 130, the second being through wire 183, relay coil 111 of the relay 110 and wire 184 back to the other line wire 130, and the third being through wire 183, relay coil 115 of the relay 114 and wire 185 back to the other line wire 130. Therefore, when the mercury switch 179 is moved to a circuit making position the relay coils 107, 111 and 115 are energized.

Energization of the relay coil 107 causes movement of the switch arm 108 into engagement with the contact 109 to complete a circuit from the line wire 129 through wire 181, electrically operated circulating pump 33, wire 188, contact 109, switch arm 108 and wire 189 back to the other line wire 130. This causes operation of the circulating pump 33 to circulate the chilled water through the cooling coil 31 located in the conditioning unit 32.

Energization of the relay coil 111 causes movement of the switch arm 112 into engagement with the contact 113 to complete a circuit from the line wire 129, through wire 190, switch arm 112, contact 113, wire 191, electrically operated fan or blower 26 and wire 192 back to the other line wire 130. This causes operation of the fan or blower to increase the cooling action of the cooling tower 23.

Energization of the relay coil 115 moves the switch arm 116 into engagement with the con-

tact 117 to complete a circuit from the line wire 129, through wire 193, switch arm 118, contact 117, wire 194, electrically operated circulating pump 24 and wire 195 back to the other line 5 wire 130. This causes operation of the pump 24 to convey warm condensing water from the condenser 12 to the cooling tower 23 and to convey the cooled condensing water from the cooling tower 23 back to the condenser 12.

10 Summarizing briefly the operation of my control system as applied to a steam jet or ejector type refrigerating system having an evaporator, a steam jet ejector, a condenser and a boiler, it is seen that upon a call for cooling the vacuum pump 19 associated with the condenser 12 is placed in operation to create a predetermined vacuum within the condenser. When the vacuum has reached a predetermined value, say 26 inches of mercury, the boiler 16 is placed in operation to produce steam to be supplied to the ejector 11. The operation of the boiler is safe-guarded by means of a high limit controller 45, a low-water cut-off mechanism 43 and a safety pilot arrangement 40. When the boiler 16 has 25 produced steam at 13 pounds pressure the valve 14 controlling the flow of such steam to the ejector 11 is opened whereby the refrigerating mechanism is placed in operation. The refrigerating mechanism is safe-guarded by the temperature responsive devices 53 and 10 to prevent operation of the refrigerating mechanism in case the evaporator temperature or chilled water temperature should decrease to a predetermined low value, or increase to a predetermined high value. Opening of the valve 14 in this manner likewise causes operation of the circulating pump 33 for circulating the chilled water through the cooling coil 31 of the air conditioning unit 32, causes operation of the circulating pump for 40 circulating the condensing water through the condenser 12 and the cooling tower 23, and causes operation of the blower or fan 28 to increase the cooling action of the cooling tower 23. When the condition to be controlled is restored to the desired value the firing of the boiler 16 is prevented and the vacuum on the condenser 12 is broken. This allows a decrease in boiler pressure and when the boiler pressure has decreased to a predetermined amount of 10 pounds the valve 14 is closed and the refrigerating mechanism is placed out of operation and the circulation of the chilled water, the circulation of the condensing water and the operation of the blower or fan is stopped.

55 From a practical standpoint the steam jet ejector 11 cannot be operated unless there is a proper vacuum since steam cannot be generated in the boiler 16 unless there is a proper vacuum. However, it may happen that the vacuum in the condenser 12 is less than the desired 26 inches of mercury, and at the same time there may be sufficient steam present in the boiler 16 to cause opening of the steam valve 14. If it is desired to eliminate this remote possibility, the vacuum responsive switching mechanism 51 may be removed from in circuit with the primary 140 of the step-down transformer 141 and placed in circuit with the motor 17 for operating the steam valve 14, such a change requiring a double-ended 60 mercury switch rather than the single-ended mercury switch shown. This change in connections might have the further advantage of allowing the vacuum to be produced and steam pressure generated concurrently so that the proper 70 vacuum and the proper steam pressure would

be established more quickly upon a demand for cooling by the condition responsive device 53.

From the above it is seen that I have provided a novel control arrangement for use with a steam jet or ejector type refrigerating mechanism, 5 wherein such a mechanism is efficiently operated, and wherein safe-guards are provided whereby the refrigerating mechanism will be shut down in case of dangerous or faulty operation.

10 Although I have disclosed one form of my invention, modifications thereof will become apparent to those skilled in the art and, consequently, this invention is to be limited only by the scope of the appended claims and the prior 15 art.

I claim as my invention:

1. In a cooling system having a condenser, an ejector, an evaporator and a steam boiler, the combination of means responsive to a demand 20 for cooling for producing a vacuum in the condenser, means responsive to the production of a predetermined vacuum in the condenser for firing the boiler to increase the boiler steam pressure, and means responsive to a predetermined steam 25 pressure for placing the ejector in operation.

2. In a cooling system having a condenser, an ejector, an evaporator and a steam boiler, the combination of means responsive to a demand 30 for cooling for producing a vacuum in the condenser, means responsive to the production of a predetermined vacuum in the condenser for firing the boiler to increase the boiler steam pressure, means responsive to a predetermined steam pressure for placing the ejector in operation, and 35 means responsive to a predetermined low evaporator temperature for stopping operation of the ejector.

3. In a cooling system having a condenser, an ejector, an evaporator and a steam boiler, the 40 combination of means responsive to a demand for cooling for producing a vacuum in the condenser, means responsive to the production of a predetermined vacuum in the condenser for firing the boiler to increase the boiler steam pressure, 45 means responsive to a predetermined steam pressure for placing the ejector in operation, and means responsive to a predetermined high evaporator temperature for stopping operation of the ejector.

50 4. In a cooling system having a condenser, an ejector, an evaporator and a steam boiler, the combination of means responsive to a demand for cooling for producing a vacuum in the condenser, means responsive to the production of a predetermined vacuum in the condenser for firing the boiler to increase the boiler steam pressure, 55 means responsive to a predetermined steam pressure for placing the ejector in operation, and means responsive to predetermined high and low 60 evaporator temperatures for stopping operation of the ejector.

5. In a cooling system having a condenser, an ejector, an evaporator, a steam boiler and a cooling device, the combination of means responsive 65 to a demand for cooling for producing a vacuum in the condenser, means responsive to the production of a predetermined vacuum in the condenser for firing the boiler to increase the boiler steam pressure, and means responsive to a predetermined steam pressure for placing the ejector in operation and for circulating cooling fluid 70 from the evaporator to the cooling device.

6. In a cooling system having a condenser, an ejector, an evaporator, a steam boiler and a

cooling device, the combination of means responsive to a demand for cooling for producing a vacuum in the condenser, means responsive to the production of a predetermined vacuum in the condenser for firing the boiler to increase the boiler steam pressure, means responsive to a predetermined steam pressure for placing the ejector in operation and for circulating cooling fluid from the evaporator to the cooling device, and means responsive to evaporator temperature for stopping operation of the ejector and circulation of the cooling fluid.

7. In a cooling system having a condenser, an ejector, an evaporator and a steam boiler, the combination of means responsive to a demand for cooling for producing a vacuum in the condenser, means responsive to the production of a predetermined vacuum in the condenser for firing the boiler to increase the boiler steam pressure, and means responsive to a predetermined steam pressure for placing the ejector in operation and for supplying condensing fluid to the condenser.

8. In a cooling system having a condenser, an ejector, an evaporator and a steam boiler, the combination of means responsive to a demand for cooling for producing a vacuum in the condenser, means responsive to the production of a predetermined vacuum in the condenser for firing the boiler to increase the boiler steam pressure, means responsive to a predetermined steam pressure for placing the ejector in operation and for supplying condensing fluid to the condenser, and means responsive to evaporator temperature for stopping operation of the ejector and the supply of condensing fluid to the condenser.

9. In a cooling system having a condenser, an ejector, an evaporator, a steam boiler and a cooling device, the combination of means responsive to a demand for cooling for producing a vacuum in the condenser, means responsive to the production of a predetermined vacuum in the condenser for firing the boiler to increase the boiler steam pressure, and means responsive to a predetermined steam pressure for placing the ejector in operation, for circulating cooling fluid from the evaporator to the cooling device and for supplying condensing fluid to the condenser.

10. In a cooling system having a condenser, an ejector, an evaporator, a steam boiler and a cooling device, the combination of means responsive to a demand for cooling for producing a vacuum in the condenser, means responsive to the production of a predetermined vacuum in the condenser for firing the boiler to increase the boiler steam pressure, means responsive to a predetermined steam pressure for placing the ejector in operation, for circulating cooling fluid from the evaporator to the cooling device and for supplying condensing fluid to the condenser, and means responsive to evaporator temperature for stopping operation of the ejector, for stopping

circulation of the cooling fluid and for stopping the supply of condensing fluid to the evaporator.

11. In a cooling system having a condenser, an ejector, an evaporator and a steam boiler, the combination of means responsive to a demand for cooling for producing a vacuum in the condenser, means responsive to the production of a predetermined vacuum in the condenser for firing the boiler to increase the boiler steam pressure, means responsive to a predetermined steam pressure for placing the ejector in operation, and time controlled means for rendering said means responsive to a demand for cooling inoperative. 5

12. A cooling system having a condenser, an evaporator and an ejector, the combination of means responsive to a demand for cooling for producing a vacuum in the condenser, and means responsive to the production of a vacuum in the condenser for placing the ejector in operation and for supplying condensing fluid to the condenser. 15

13. A cooling system having a condenser, an evaporator and an ejector, the combination of means responsive to a demand for cooling for producing a vacuum in the condenser, means responsive to the production of a vacuum in the condenser for placing the ejector in operation and for supplying condensing fluid to the condenser, and means responsive to evaporator temperature for stopping operation of the ejector and for stopping the supply of condensing fluid to the condenser. 25

14. A cooling system having a condenser, an evaporator, an ejector and a cooling device, the combination of means responsive to a demand for cooling for producing a vacuum in the condenser, and means responsive to the production of a vacuum in the condenser for placing the ejector in operation and for circulating cooling fluid from the evaporator to the cooling device. 30 40

15. A cooling system having a condenser, an evaporator, an ejector and a cooling device, the combination of means responsive to a demand for cooling for producing a vacuum in the condenser, means responsive to the production of a vacuum in the condenser for placing the ejector in operation and for circulating cooling fluid from the evaporator to the cooling device, and means responsive to evaporator temperature for stopping operation of the ejector and circulation of the cooling fluid. 45 50

16. A cooling system having a condenser, an evaporator and an ejector, the combination of means responsive to a demand for cooling for producing a vacuum in the condenser, means responsive to the production of a vacuum in the condenser for placing the ejector in operation, and time controlled means for rendering said means responsive to a demand for cooling inoperative at predetermined times. 55 60
